UNITED STATES PATENT OFFICE.

HARRIS F. WELLS, OF FRIENDSHIP, NEW YORK, ADMINISTRATOR OF ALBERT F. WELLS, DECEASED.

CALENDAR-CLOCK.

SPECIFICATION forming part of Letters Patent No. 407,977, dated July 30, 1889.

Application filed January 22, 1889. Serial No. 297,107. (No model.)

To all whom it may concern:

Be it known that ALBERT F. WELLS, late a citizen of the United States, residing at Friendship, in the county of Allegany and State of New York, deceased, did invent a new and useful Improvement in Calendar-Clocks, of which the following is a specification.

This invention relates to improvements in calendar-clocks, and has for its object to simplify the mechanism whereby the month wheel or cylinder is actuated at variable intervals of time rendered necessary by the difference in length of the thirty and thirty-one day months and the month of February, and by the change in the number of days in the latter month every four years.

The invention consists of the improvements which will be hereinafter fully described, and pointed out in the claims.

In the accompanying drawings, consisting of two sheets, Figure 1 is a sectional front elevation of the improved calendar-clock, the dial-inclosing frame being omitted. Fig. 2 is a top plan view thereof. Fig. 3 is a cross-section in line $x-x$, Fig. 1, looking toward the month-cylinder. Fig. 4 is a cross-section in line $y-y$, Fig. 1, looking in the opposite direction, showing the movable pin attached to the actuating-wheel of the month-cylinder and the mechanism whereby the same is released and held rigid. Figs. 5 and 6 are elevations of the main actuating-wheel and connecting parts, showing different positions of the movable detent-releasing frame attached to said actuating-wheel. Fig. 7 is a fragmentary elevation of the actuating-wheel of the day-cylinder and its operating mechanism.

Like letters of reference refer to like parts in the several figures.

A represents the stationary supporting plate or frame, carrying the parts of the calendar mechanism, and which is secured to the rear wall of the clock-easing in the usual way.

B is the revolving cylinder indicating the days of the week, and B' the cylinder indicating the months of the year. These cylinders are each provided with a sleeve or hollow axle b , which sleeves turn upon opposite ends of a stationary spindle b' . The latter is

supported centrally in a bearing b^2 , secured to a forwardly-projecting bracket b^3 , attached to the supporting-plate A.

C represents the upright actuating-rod of the calendar mechanism, which is connected with the clock-work in any suitable and well-known manner, so as to be reciprocated once every twenty-four hours. The rod C is guided at its lower end by straddling the bracket b^3 with its lower bifurcated portion c , and at its upper end by clinch-pins c' or other means.

D is a toothed actuating-wheel mounted on the axle of the day-cylinder B, and which is intermittently turned by means of an actuating-pawl d , hung to an upwardly-bent arm d' , formed on the adjacent side of the actuating-rod C and engaging with the teeth of said wheel, as represented in Figs. 1 and 7.

d^2 , Figs. 1, 2, and 7, is a spring-detent engaging with the upper side of the actuating-wheel D and provided with a downwardly-projecting arm d^3 , which is struck by an inclined foot at the lower end of the pawl d when the actuating-rod C is depressed, so as to disengage the detent from the wheel D and allow the actuating-pawl to turn the wheel the distance of one tooth. The day-wheel may be operated from the actuating-rod C in any other manner, if desired.

E represents an actuating crown-wheel having twelve teeth and mounted on the axle b of the month-cylinder B' on the inner side of the latter, and e is a vertically-swinging detent pivoted to the outer end of the bracket b^3 and engaging in the spaces between the teeth of said crown-wheel, as represented in Figs. 2 and 3, so as to hold the same against turning. The detent e is held in an elevated position in engagement with the teeth of the crown-wheel by a spring e' .

F represents the main toothed actuating-wheel, which is provided with thirty-one teeth, and is mounted upon a horizontal shaft f , arranged at right angles to the spindle b' , and journaled at its inner end in an opening in the supporting-plate A and at its outer end in a bearing f' at the front end of the bracket b^3 . An intermittent rotary motion is imparted to the main wheel F once in every twenty-four hours by a weighted pawl f^2 , piv-

oted to a lateral arm f^3 , formed on the actuating-rod C and engaging with the teeth of said wheel, as clearly shown in Figs. 1, 2, and 6.

f^4 is a spring-detent pivoted to the support-
5 ing-plate A and engaging between the teeth
of the main wheel F. This detent is disen-
gaged from the wheel F when the actuating-
rod C is depressed by a projection f^5 , arranged
10 on said rod and striking an arm f^6 , formed on
the detent, said projection being inclined so
as to allow the arm f^6 to ride over the projec-
tion when the actuating-rod is elevated.

g is a revolving trip-finger pivoted at its in-
15 ner bifurcated end to the shaft f , so as to
swing laterally in the longitudinal direction
of said shaft, and which is adapted to pass
with its outer end through the notch or space
20 of the crown-wheel in which the detent e is
seated and depress the latter, so as to disen-
gage it from the teeth of the crown-wheel and
permit the latter to be turned.

H is a stationary spiral cam or guide sur-
rounding the shaft f in rear of the trip-finger
 g and supported upon the bracket b^3 , as shown
25 in Fig. 4. The trip-finger g bears against the
front side of the spiral cam H, and is held
against the same by a spiral spring g' , sur-
rounding the shaft f , and secured at one end
30 to the shaft and at its other end to the trip-
finger. The front end of the cam H termi-
nates adjacent to the free end of the detent
 e , and the rear end of the cam is arranged the
distance of one notch or tooth of the crown-
35 wheel in rear of the front end of the cam, so
that as the trip-finger revolves with the shaft
 f it is gradually moved forward by the cam
and guided into and through the notch in
which the detent e is located, thereby de-
pressing the detent out of engagement with
40 the teeth of the crown-wheel and releasing
the latter. At the moment that the detent is
disengaged from the crown-wheel the trip-
finger g clears the front end of the cam H and
is drawn rearwardly against the rear or ini-
45 tial end of the cam by the spring g' , thereby
striking the adjacent tooth of the crown-
wheel, shifting the latter with the month-cyl-
inder forwardly the distance of one tooth and
exposing the name of the next month through
50 the slot in the dial of the clock. As soon as
the crown-wheel has been shifted the detent
engages in the next notch thereof and arrests
its further movement. It will thus be seen
55 that, as the main wheel F has thirty-one teeth,
and the actuating-rod C moves the same the
distance of one tooth every day, the trip-finger
 g makes one revolution every thirty-one days,
or, in other words, at the end of every long
60 month, and thereby shifts the month-cylinder
the distance of one tooth of its actuating-
wheel.

The mechanism so far described relates to
the long months, or those having thirty-one
days. In order to shift the month-cylinder
65 at the end of the thirty-day months and of
February having either twenty-eight or
twenty-nine days, the main wheel F and trip-

finger g must make a complete revolution
either with twenty-eight, twenty-nine, or
thirty strokes of the actuating-rod C, as the
70 latter is actuated but once every day. The
mechanism for accomplishing this consists of
the following:

I represents a movable detent-releasing
frame pivoted to the front side of the main
wheel F, and consisting of a segment i , which
75 is adapted to cover three of the teeth of the
main wheel F, a lifting arm or foot i' , ar-
ranged adjacent to the periphery of the crown-
wheel E, and an arm i^2 , whereby the frame I
80 is pivoted to the wheel F. The movable frame
I is capable of oscillating on the wheel F, so
as to cause its segment i to cover or uncover
the adjacent teeth of the main wheel F, and
it is provided at its center with a semicircular
85 jaw or recess i^3 , which loosely straddles the
shaft f and limits the oscillating movement
of the releasing-frame by striking either side
of said shaft, as clearly shown in Figs. 1, 5,
90 and 6.

j represents radial pins or projections ar-
ranged on the periphery of the crown-wheel
E, and over which the outer end of the lifting-
foot i' rides as the wheel F revolves, thereby
moving the segment i outwardly and causing
95 it to cover the adjacent teeth of the wheel F.
The lifting-foot is provided at its outer end
with an inclined nose i^4 to facilitate the move-
ment of the foot over the pins j on striking the
latter. A pin j is arranged on the crown-wheel
100 F about diametrically opposite the name of
every month on the month-cylinder having
thirty days, so that on the last day of a thirty-
day month a pin will stand in the path of the
lifting-foot i' of the detent-releasing frame
105 ready to actuate said foot at the next revolu-
tion of the latter. In riding over such a pin
the foot i' is elevated, thereby projecting the
segment i in line with the three adjacent
110 teeth of the wheel F and substituting prac-
tically one wide tooth for three narrow ones
on the wheel F. It will now be obvious that
the outward movement of the segment i may
be so timed as to cause the detent f^1 to ride
115 over the entire surface of said movable seg-
ment, and thereby skip three teeth of the
main wheel F, or to ride over two-thirds
of the segment and skip two teeth of said
wheel, or to ride over but one-third thereof,
120 so as to skip but one of the teeth of said
wheel. The pins coinciding with the thirty-
day months are so placed with reference to
the lifting-foot i' that the segment i will be
projected just at the proper time to cause the
detent to ride over only the last third of said
125 tooth, so as to skip one tooth of the main
wheel F. On the last day of the thirty-day
month the wheel F will now be moved the
distance of two of its teeth by the actuating-
rod C, thereby causing the trip-finger g to
130 travel twice its usual distance on this last day,
and shifting the month-cylinder at the proper
time to again bring the trip-finger to the ini-
tial end of the cam on the first day of the

new month. The nose or head at the lower end of the lifting-foot i' is made of such width that the segment i will be held in a projected position just a sufficient time to cause the 5 detent f^4 to skip one tooth of the wheel F , the frame I falling away from the teeth of the wheel F by gravity when the lifting-foot has passed a pin j , thereby uncovering said teeth and allowing the detent f^4 to again engage 10 successively with all of the teeth of the wheel B until a pin again stands in the path of said lifting-foot.

About diametrically opposite the name of the month of February on the month-cylinder are arranged three pins k k' k^2 , one in advance of the other and concentric with the center of the main wheel F , so as to hold the lifting-foot in an elevated position and the segment i in a projected position during the 15 time required by the detent-pawl f^4 to ride over the entire surface of the movable segment, and thus cause the main wheel to be moved the distance of three teeth by the actuating-rod C on the last day of the month 20 and the trip-finger g three times its usual distance, thereby shifting the month-wheel just at the proper time to cause the trip-finger g to again begin its travel around the cam H on the first day of the new month.

25 As the month of February has twenty-nine days every four years, or at leap-year, it is necessary to cause the lifting-foot i' to be held in an elevated position and the segment i to be retained in a projected position during the time required by the detent f^4 to ride over two-thirds of said segment, so that the 30 detent will skip two teeth of the main wheel F , and thereby cause the wheel F and trip-finger g to make a complete revolution with twenty-nine strokes of the actuating-rod C . 35 This is accomplished by making one of the pins k k' k^2 movable, preferably the outer one k^2 , so that the same may stand parallel or in line with the adjacent stationary pin k' , and thus leave practically but two operative pins, and providing mechanism whereby 40 said movable pin is held rigid during the ordinary three years, when February has twenty-eight days, and released at the fourth 45 or leap year, when said month has twenty-nine days.

The movable pin consists of a piece of wire, which is pivoted at its inner end to the central or hub portion of the crown-wheel E , and 50 is guided at its outer portion by a strap or hook l , secured to the side of the crown-wheel.

m is a revolving cam mounted on a spindle turning in the crown-wheel and cut away or flattened on one side, as shown at m' in Fig. 60 4. When this cam rests with its curved edge against the pin k^2 , as shown in said figure, the pin is held rigidly away from the adjacent stationary pin, while when the flat side of the cam is presented to the pin the latter 65 is released and allowed to occupy a position parallel with said adjacent pin by gravity, as represented in Fig. 6, in which position it is

inoperative and does not affect the lifting-foot i' .

n is a four-armed wheel of the shape of a Maltese cross, secured to the spindle of the cam m on the inner side of the crown-wheel, so as to revolve with the latter, and o is a stationary wheel or disk secured to the stationary spindle b' , and having a tooth or projection o' , which 70 engages successively with the arms or teeth of the wheel n . As the month-cylinder revolves, the stationary tooth o' strikes one of the teeth of the wheel n , and thereby turns the latter with the cam m the distance of one tooth every year. At the end of February of the fourth or leap year the wheel n will complete its revolution and bring the flat side of the cam m opposite the pin k^2 , thereby releasing the latter. Before February of the next 75 year is reached the wheel m will again be moved the distance of one tooth, thereby bringing the curved portion of the cam against the pin, moving the latter away from the adjacent stationary pin and again holding the same rigidly in place, as shown in Fig. 4. In this manner the movable pin is held rigidly during three years, so as to be operative, and is released at leap-year, so as to be inoperative.

95 What is claimed as the invention of the said ALBERT F. WELLS is—

1. The combination, with the revolving month-cylinder provided with a toothed actuating-wheel, of a detent whereby the same is held against turning, a revolving actuating-shaft, means whereby an intermittent rotary motion is imparted to said shaft, and a revolving trip-finger attached to said shaft and adapted to disengage said detent from said actuating-wheel, substantially as set forth.

2. The combination, with the revolving month-cylinder provided with a toothed actuating-wheel, of a detent engaging with said wheel, a revolving actuating-shaft, means whereby an intermittent rotary motion is imparted to said shaft, a laterally-movable trip-finger pivoted to said shaft, so as to revolve therewith, and adapted to disengage the detent from said wheel, and a cam whereby said trip-finger is guided to said detent, substantially as set forth.

3. The combination, with the revolving month-cylinder provided with a toothed actuating-wheel, of a detent engaging with said wheel, a revolving actuating-shaft, means whereby an intermittent rotary motion is imparted to said shaft, a laterally-movable trip-finger pivoted to said shaft, so as to revolve therewith, and adapted to disengage the detent from said wheel, a cam whereby said trip-finger is guided to said detent, and a spring whereby said trip-finger is held against the cam and the finger and month-wheel are shifted when the trip-finger clears said cam, substantially as set forth.

4. The combination, with the revolving month-cylinder provided with a crown-wheel having twelve teeth, of a vertically-swinging

detent engaging with said teeth, a revolving shaft provided with an actuating-wheel having thirty-one teeth, a laterally-movable trip-finger pivoted to said shaft, a spiral cam 5 whereby said trip-finger is guided to the detent, and a spring whereby said trip-finger is held against the cam, substantially as set forth.

5. The combination, with a horizontal shaft, of a main actuating-wheel attached to said 10 shaft and having thirty-one teeth, pawl mechanism whereby an intermittent rotary motion is imparted to said wheel, a detent engaging with said wheel, a movable detent-releasing frame arranged on said actuating - wheel, 15 a month-cylinder having an actuating-wheel, which is operated from said horizontal shaft, and pins arranged on said actuating-wheel, and with which said detent-releasing frame engages, substantially as set forth.

20. 6. The combination, with a horizontal shaft, of a main actuating-wheel attached to said shaft and having thirty-one teeth, an actuating rod and pawl whereby an intermittent rotary motion is imparted to said wheel, a detent engaging with said wheel, a movable detent-releasing frame pivoted to said wheel and 25 consisting of a segment adapted to cover several teeth of the actuating-wheel and a lifting foot or arm, a month-cylinder provided 30 with an actuating-wheel having twelve teeth, pins attached to said actuating-wheel, whereby said lifting-foot is actuated, a detent engaging with said wheel, and a revolving trip-finger attached to said horizontal shaft, 35 whereby said detent is disengaged from the actuating-wheel of the month-cylinder, substantially as set forth.

7. The combination, with a horizontal shaft, of a main actuating-wheel attached to said 40 shaft and having thirty-one teeth, pawl mechanism whereby an intermittent rotary motion is imparted to said wheel, a detent engaging with said wheel, a movable detent-releasing

frame pivoted to said actuating-wheel and 45 consisting of a segmental plate and a lifting- foot, a month-cylinder provided with an actuating-wheel having twelve teeth and operated from said horizontal shaft, one or more stationary pins arranged on the actuating-wheel of the month-cylinder in the path of said lifting-foot, and a movable pin, also arranged on said actuating - wheel adjacent to said stationary pin or pins, substantially as set forth. 50

8. The combination, with a horizontal shaft, of a main actuating-wheel attached to said 55 shaft and having thirty-one teeth, pawl mechanism whereby an intermittent rotary motion is imparted to said wheel, a detent engaging with said wheel, a movable detent-releasing frame pivoted to said actuating-wheel and 60 consisting of a segmental plate and a lifting- foot, a month-cylinder provided with an actuating-wheel having twelve teeth and operated from said horizontal shaft, one or more stationary pins arranged on the actuating-wheel 65 of the month-cylinder in the path of said lifting-foot, a movable pin arranged on said actuating-wheel adjacent to said stationary pin or pins and capable of standing in line with one of said stationary pins when released, a 70 revolving cam bearing against said movable pin, a revolving four-armed wheel connected with said cam and journaled on the actuating-wheel of the month-cylinder, and a stationary disk having a tooth or projection 75 engaging with the arms or teeth of said four-armed wheel, whereby the latter is turned the distance of a tooth at every revolution of the month-cylinder, substantially as set forth.

Witness my hand this 27th day of December, 1888.
